Primary Examiner — Nathan M Johnston

(74) Attorney, Agent, or Firm — Suzanne Kikel, Patent Agent

(57) **CLAIM**

The ornamental design for a towel rack, as shown and described.

DESCRIPTION

FIG. 1 is a front perspective view of a towel rack, showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof; and,

FIG. 7 is a right-side elevation view thereof.

Broken lines are used to illustrate portions of the towel rack. Other broken lines illustrate environmental subject matter that form no part of the claimed design.

1 Claim, 4 Drawing Sheets(56)
